[57] CLAIM

The ornamental design for a wheel, as shown and described.

DESCRIPTION

FIG. 1 is a front perspective view of a wheel showing the first embodiment of my new design;

FIG. 2 is a reduced front view thereof;

FIG. 3 is a reduced rear view thereof;
FIG. 4 is a reduced side view thereof, it being understood that the opposite side is a mirror image thereof; and,
FIG. 5 is a front view of a wheel showing the second embodiment of my new design with the only difference being the plain central hub area.

The broken line showing of environment is for illustrative purposes only and forms no part of the claimed design.
